DESIGN FOR A VELOCIPEDe FRAME MEMBER

Samuel A. Snell, Toledo, Ohio, assignor to The
American-National Company, Toledo, Ohio, a
corporation of Ohio

Application April 11, 1938, Serial No. 76,440

Term of patent 7 years

To all whom it may concern:

Be it known that I, Samuel A. Snell, a subject
of the King of Great Britain and Northern Ire-
land, residing at Toledo, in the county of Lucas
and State of Ohio, have invented a new, original,
and ornamental Design for a Velocipede Frame
Member, of which the following is a specification,
reference being had therein to the accompanying
drawing forming a part thereof, wherein:

Figure 1 is a front perspective view of a
velocipede frame member embodying my new
design; and

Figure 2 is a rear perspective view thereof.
I claim:

The ornamental design for a velocipede frame
member substantially as shown.

SAMUEL A. SNELL.
